UNITED STATES PATENT OFFICE

2,649,896

SPRING SEAT CUSHION

Maurice Stubnitz, Adrian, Mich., assignor to
 Stubnitz-Greene Spring Corporation, Adrian,
 Mich., a corporation of Michigan

Application December 19, 1949, Serial No. 133,724

3 Claims. (Cl. 155—179)

1

This invention relates to cushion seats for trucks and similar vehicles. It is the object of the invention not only to provide a truck seat at minimum cost, but also to provide a truck seat which will afford maximum comfort for the rider.

The invention uses a base frame of double J cross section in which the upper J bends over the turned up ends of the cross members and anchors these to the frame while the gullet of the lower J seats the turned over ends of the jack springs. These ends are anchored to the J frame by means of a turned out portion of the metal of the J frame.

Referring to the drawings:

Fig. 1 is a cross section of the invention showing the base frame formed by double J bars.

Fig. 2 is a detail of the double J bar showing how the turned over end of the jack spring is anchored in place by a turned over piece of the metal of the J bar.

Fig. 3 is a detail showing how the coil springs are anchored to the lattice like mat.

Fig. 4 is a cross section of the J frame showing how the member is pinched over and welded to the turned up cross strap end.

The spring is made up of a plurality of short conical springs 14 which are connected together at their top by means of a wire border frame 15. These springs are supported at the lower ends by means of a wire mat formed by the stringers 18 and 19 which cross each other and are interlaced into the bottom coil of the conical coil load supporting springs 14. These springs can be assembled in the mat by screwing them into the intersecting wires 18 and 19 as shown in Fig. 3. The stringers 18 are yieldable stringers supported at the front and rear by jack or safety pin type springs forming spring legs which are a continuation of the stringers 18. This construction is more thoroughly described and claimed in my prior application Serial No. 45,175, filed August 19, 1948, now Patent No. 2,642,929.

The base frame of the spring assembly is formed by channel strips 26 which are double J strips, that is, the upper edges are turned over to form the J portion 27 and the lower edges are turned over to form the lower J portion. The upper J portion 27 is adapted to be turned down to engage over the turned up ends 28 of the cross bars 29 as shown in Fig. 4. The ends of the safety pin type springs are turned over at 11a and the clip portions 31 are struck out of the metal of the double J strips and wrapped around the bent over ends 11a to hold these in place and

2

secure the jack springs to the base strip so that the legs of the jack springs can pivot when the seat spring is put under load.

What I claim is:

- 5 1. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions.
- 10 2. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions.
- 15 3. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions, the metal of the frame bar being struck out and rolled over such turned over ends of the jack springs.

- 20 3. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions, the said frame pinched over the turned
- 25 4. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions.
- 30 5. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions.
- 35 6. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions.
- 40 7. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions.
- 45 8. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions.
- 50 9. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions.
- 55 10. A seat cushion having a base frame, a spring assembly secured to the base frame, the said spring assembly comprising a plurality of coiled load supporting springs, a latticed spring mat made up of spring wire stringers crossing one another and locked into the bottom whorls of the load supporting springs, the front and rearwardly extending stringers ending in safety pin or jack springs having turned over ends which are secured to the base frame, the base frame including front and rear J strip rails, each having a double J cross-section, connected by cross straps having turned up ends over which one J portion of the strip is pinched and the turned over ends of the jack springs anchored in the gullet of the frame, between the two J portions.

over ends of the jack springs by struck out portions of the gullet formed by the lower J portion of the frame.

MAURICE STUBNITZ.
